UNITED STATES PATENT OFFICE.

FRANK OBERMULLER, OF STE. GENEVIEVE, MISSOURI.

TOOL GRIP.

Application filed February 21, 1924. Serial No. 694,330.

To all whom it may concern:

Be it known that I, FRANK OBERMULLER, a citizen of the United States, residing at Sainte Genevieve, in the county of Sainte 5 Genevieve and State of Missouri, have invented certain new and useful Improvements in Tool Grips; and I do hereby declare the following to be a full, clear, and exact description of the invention, such as 10 will enable others skilled in the art to which it appertains to make and use the same.

In the drilling of oil, artesian and other deep wells it frequently happens that the tools become fast for one reason or another 15 and time is required for loosening and recovering the same, and in many instances after hours have been spent in a vain attempt to recover the tools, the latter and the well become abandoned, thereby resulting in a considerable loss both in tools, adjunctive parts and the time expended in the 20 boring of the well to the point of abandonment.

The present invention has for its object 25 to provide a grip which may be lowered into the well and engage the tools and which is attached to and adapted to be operated independently of the rope or cable attached to the tools for operating them in the first instance, the auxiliary cable sustaining the 30 load and pull while the drilling cable may be utilized jointly with jars to effect a loosening of the tools, thereby insuring a recovery of the tools in a comparatively short time.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 45 without departing from the spirit of the invention.

Referring to the accompanying drawings forming a part of the application:

Figure 1 is a detail view illustrating the 50 application of the invention,

Figure 2 is a perspective view of the grip,

Figure 3 is a sectional view of the grip,

Figure 4 is a detail view of the plate or ring to which the dog is pivoted,

55 Figure 5 is a detail perspective view of

portions of adjacent plates or rings separated showing the opening in one and the projection on the other for closing the opening when the plates are assembled, and

Figure 6 is a detail view.

Corresponding and like parts are referred to in the following description and designated in the several views of the drawings by like reference characters.

The grip constructed in accordance with the invention comprises a plurality of plates or rings which are placed one upon the other and secured by means of bolts or analogous fastening means, each of the plates or rings having a lateral opening for the passage 60 of the rope or cable and the adjacent plate or ring having a projection to enter and close the opening whereby the body of the grip is adapted to encircle the drilling cable and the tool to be recovered, said body being provided with a dog which is pivoted thereto and adapted to securely and positively engage the tool to insure its recovery 65 after being loosened.

The body of the grip is of composite 70 structure and comprises a plurality of annular plates or rings, the number being immaterial and depending upon the thickness of the ring and the strength required of the grip to withstand the strain to which it will 75 be subjected when in active operation. The plates or rings 1 are placed one upon the other and are secured by means of bolts 2 or analogous fastening means. Each of the plates or rings 1 is provided in a side with 80 an opening 3 for the passage of the rope or cable when placing the grip in position or removing it from the cable attached to the tools. The openings 3 are located at different 85 relative points so as not to aline when the plates or rings are assembled. The adjacent plate or ring is provided with a projection 4 in position to enter and fill the opening 3 of the contiguous plate or ring and close said opening. Each of the plates 90 or rings 1 is enlarged at a point in its circumferential length and these enlargements or widened portions aline when the plates or rings are assembled and are formed with an opening through which an eyebolt 5 passes 95 and to which is attached a rope or cable 6 whereby the grip is operated when in action.

A dog 7 of crescent or semicircular form 100 is disposed within the body of the grip and is pivotally connected intermediate its ends 110

to a ring or plate thereof and is normally supported in horizontal position by an inner shoulder 8 which forms a stop or rest therefor and which is provided by the plates 5 or rings immediately below that to which the dog 7 is pivoted. The ring or plate next above that to which the dog 7 is pivoted is cut away opposite the pivot of the dog to provide ample clearance for the latter so 10 that its free end may rise when lowering the grip and the dog 7 engages and rides upon the tool 9 to be recovered from the well. The active or biting edge of the dog 7 is beveled to insure a positive grip between the 15 dog and tool so that sufficient force may be exerted to extract and recover the tool.

In practice, when a tool 9 becomes fast in the well and cannot be removed in the ordinary manner and by the usual means 20 employed, the grip may be employed and the same is dismembered and each plate or ring is separately placed in position about the drilling cable 10, the openings 3 admitting of the placing of the plate in position. After all the plates or rings 1 have 25 been assembled about the cable 10, they are brought together and made secure by means of the bolts 2 and the eyebolt 5, the openings 3 being closed by the projections 4. The operating rope or cable 6 is attached to 30 the eyebolt 5 and the grip is lowered into the well and is guided by the cable 10 to the tool 9 and slips upon the latter and is made fast thereto by means of the dog 7 when a pulling force is applied to the rope or cable 35 6. The drilling cable 10 may be operated in the usual way to effect a loosening of the tool and this may be supplemented by a pull force upon the cable 6 and the combined action of the two cables usually results in a 40 recovery of the tool which otherwise could not be effected by the operation of the drill cable alone in the ordinary manner of operation.

What is claimed is:

1. A grip for recovering a tool which has become fast in a deep well, the same comprising a plurality of plates, each plate having an opening for the passage of the drilling cable and the adjacent plate having a 50 projection to snugly fit and close the opening, fastening means for securing the plates when assembled, and a dog applied to the body of the grip for positively engaging the tool to be recovered. 55

2. A grip for recovering a tool which has become fast in a deep well, the same comprising a plurality of plates, each plate having an opening for the passage of the drilling cable and the adjacent plate having a projection to snugly fit and close the opening, fastening means for securing the plates when assembled, and a dog applied to the body of the grip for positively engaging the tool to be recovered, certain 60 plates below the dog forming a stop shoulder therefor and the plate next above the dog being cut away to provide clearance to allow for the pivotal movement of the dog. 65

3. A grip of the character specified comprising a plurality of plates placed one upon the other, each having a side opening and the adjacent plate having a projection to fit the opening of the contiguous plate, fastening means for securing the plates when 70 assembled, a dog pivoted to one of the plates and normally supported in operative position by the plate next below that to which the dog is pivoted, and an eyebolt serving as supplementary means to connect the plates 75 and adapted to receive the operating rope or cable. 80

In testimony whereof I affix my signature in presence of two witnesses.

FRANK OBERMULLER.

Witnesses:

STEVE ROTH,
AUGUST W. BRECKLE.
